HEATING PAD SWITCH OR THE LIKE

Donald B. Lowe, Jr., Batavia, Ill., assignor to Northern Electric Company, Chicago, Ill., a corporation of Delaware

Filed Jan. 30, 1961, Ser. No. 63,764

Term of patent 14 years

(Cl. D26—13)

FIG. 1

FIG. 2

FIG. 4

FIG. 3

FIGURE 1 is a front elevational view of a heating pad switch, or the like, showing my new design;

FIGURE 2 is a side elevational view thereof;

FIGURE 3 is a top plan view thereof; and

FIGURE 4 is a side elevational view thereof, partially broken away and shown in cross-section.

The back and bottom sides are plain and unornamented.

The dominant features of my design reside in the full line of portions of the drawings.

I claim:

The ornamental design for a heating pad switch or the like, substantially as shown and described.
